UNITED STATES PATENT OFFICE.

OTTO H. WANDERSEE, OF ROCHESTER, NEW YORK.

REPRODUCER FOR TALKING-MACHINES.

1,380,445.

Specification of Letters Patent. Patented June 7, 1921.

Application filed July 7, 1920. Serial No. 394,433.

To all whom it may concern:

Be it known that I, Otto H. WANDERSEE, a citizen of the United States, and resident of Rochester, in the county of Monroe and State New York, have invented certain new and useful Improvements in Reproducers for Talking-Machines, of which the following is a specification.

The present invention relates to reproducers for talking machines and more particularly to the mounting of the stylus lever, an object of this invention being to provide a mounting which may be readily changed to obtain different tones from the reproducer.

To this and other ends, the invention consists of certain parts and combinations of parts all of which will be hereinafter described, the novel features being pointed out in the appended claims.

In the drawings:

Figure 1 is a plan view, partially in section, of a reproducer embodying the present invention;

Fig. 2 is an edge view of the reproducer partially in section;

Fig. 3 is a section through one of the blocks employed for supporting the stylus lever, the section being taken on the line 3—3, Fig. 4.

Fig. 4 is a bottom view of one of the blocks;

Fig. 5 is an end view of one of the blocks;

Fig. 6 is a fragmentary enlarged view showing the stylus lever connected to one of the blocks;

Fig. 7 is a view similar to Fig. 6 showing the block in section on the line 7—7, Fig. 8;

Fig. 8 is a view of the parts illustrated in Figs. 6 and 7, showing a section on the line 8—8, Fig. 6;

Fig. 9 is a detail view of one of the extensions of the stylus lever;

Fig. 10 is a perspective view of one of the sound pieces;

Fig. 11 shows in plan view, a modification of the reproducer from that illustrated in Figs. 1 to 10 inclusive;

Fig. 12 is a section on the line 12—12, Fig. 14;

Fig. 13 is an edge view of the parts illustrated in Fig. 12; and

Fig. 14 is a section on the line 14—14, Fig. 11.

Referring more particularly to the drawings, 1 indicates the reproducer casing or

housing and 2 the diaphragm which has a stylus lever 3 secured thereto at the center thereof at 4 and provided with a clamp 5 for holding the stylus 6.

With the end in view of mounting the stylus lever 3 on the casing 1, two blocks 7 are provided which rest upon seats formed on the ears 8 on said casing 1, said ears also having shoulders or abutments 9 engaged by the blocks at the sides of the latter. Each block is preferably held to its seat against the shoulder by a screw 10 passing through an ear 8 and into an opening 11 formed in the under side of the block. The blocks are also provided each with a central opening 12 and a slot or pocket 13 intersecting said central opening and also the bottom face of the block. A sounding piece 14 made of wood, hard rubber, metal or any other desired material, is inserted in this pocket 13 for the purpose of providing a support for the stylus lever.

In order to support the stylus lever on the sounding pieces 14, the stylus lever preferably has arms 15 projecting in opposite directions from the sides thereof and provided with screw threaded openings 16 in their ends. Into these screw threaded openings are secured extensions each of which comprise a screw threaded portion 17 fitted in a screw threaded opening 16, a reduced cylindrical portion 18 adapted to rest in a seat 21 formed in a sounding piece 14, a shoulder 19, and a portion 20 of rectangular cross section. Each extension is also provided at its end with a slot 22 in which a screw driver or other tool may be introduced for the purpose of drawing the shoulder 19 firmly against one face of the sounding piece 14 so that the arms 15 are supported under tension on the two sounding pieces 14. In order to hold the arms 15 on the two sounding pieces, each block 7 has a set screw 23 passing through the top wall thereof and engaging the cylindrical portion 18 of the extension in line with the plane of the sounding piece 14. Each block also has a set screw 24 for engagement with the portion 20 of the extension, a piece of rubber 25 or other sound deadening material preferably being interposed between the screw 24 and the extension.

Instead of using the sounding pieces 14 the stylus lever may be supported on knife edges in the manner illustrated in Figs. 11 to 14 inclusive and to this end the extensions

are each provided with a longitudinally extending slot 26 which, when the extensions are screwed tightly in the arms 15, face toward the diaphragm 2. One of the side walls of each of the blocks 7 has a screw 27 mounted therein and provided with a knife edge 28 which projects into the slot 26. The opposite wall of the block 27 has a screw 29 which co-operates with the opposite side of 10 the extension, a sound deadening piece 30 being preferably interposed between the screw 29 and the extension. This arrangement provides a knife edge mounting of the arms 15 on the housing of the reproducer.

15 From the foregoing it will be seen that there has been provided a reproducer in which the stylus lever is supported in blocks in such a manner that the lever may be adjusted to obtain various mountings therefor.

20 The stylus lever has extensions, which in one instance are adjustable to produce a tension on the sounding pieces and in another instance are firmly held to the lever so that a knife edge mounting of the lever may be 25 obtained.

What I claim as my invention and desire to secure by Letters Patent is:

1. The combination with a reproducer casing and a stylus lever having arms projecting from opposite sides thereof, of adjustable extensions mounted in said arms and having abutments thereon and sounding pieces on which said adjustable extensions are held, said sounding pieces being engaged by said 35 abutments.

2. The combination with a reproducer casing and a stylus lever having laterally extending arms, of a pair of extensions adjustable in said arms and provided with abutments, sounding pieces on which said extensions are held, said pieces being engaged on the sides by the abutments, and removable blocks secured to the reproducer casing and supporting said sounding pieces.

45 3. The combination with a reproducer casing and a stylus lever, of seats on said casing, shoulders adjacent said seats, blocks held to the seats and having central openings and slots in their bottom walls intersecting said openings, sounding pieces arranged in said slots, and adjustable extensions on the stylus lever held to said sounding pieces.

50 4. The combination with a reproducer casing and a stylus lever, of seats on the casing, shoulders adjacent said seats, blocks resting on said seats against the shoulders and having central openings and pockets extending through the under faces and intersecting said central openings, sounding

pieces in said pockets, and extensions having screw threaded engagement with the stylus lever resting upon said sounding pieces and having annular abutments engaging the sides of said sounding pieces.

5. The combination with a reproducer casing, of a stylus lever having laterally extending arms provided with screw threaded openings, extensions secured in said openings, and means for supporting said extensions.

6. The combination with a reproducer casing, of a stylus lever having laterally extending arms provided with screw threaded openings, extensions secured in said openings, means for supporting said extensions comprising sounding pieces on which said extensions rest, and screws for holding said extensions in co-operation with said sounding pieces.

7. The combination with a reproducer casing, of blocks removably secured to said casing, sounding pieces removably arranged in said blocks, a stylus lever, and adjustable extensions carried by said stylus lever and held to said sounding pieces.

8. The combination with a reproducer casing, of sounding pieces arranged on said casing, a stylus lever, and adjustable extensions having screw threaded engagement with said lever, held to said sounding pieces and having surrounding shoulders engaging the sides of said sounding pieces.

9. The combination with a reproducer casing, of sounding pieces arranged on said casing, a stylus lever, adjustable extensions having screw threaded engagement with said stylus lever, bearing on said sounding pieces and having annular shoulders engaging with said sounding pieces, and screws for holding said adjustable extensions against the sounding pieces.

10. The combination with a reproducer casing and a stylus lever, of blocks on said casing having openings, extensions on the stylus lever projecting into said openings, and means arranged on said blocks for removably securing said extensions in said openings.

11. The combination with a reproducer casing and a stylus lever, of blocks on said casing having openings, extensions on the stylus lever projecting into said openings, and means arranged on said blocks for removably securing said extensions in said openings, said means comprising removable sounding pieces and screws holding said extensions against said sounding pieces.

OTTO H. WANDERSEE.
